UNITED STATES PATENT OFFICE

FRANK A. DONALDSON, OF MINNEAPOLIS, MINNESOTA

AIR CLEANER AND COUPLING

Application filed August 1, 1929. Serial No. 382,686.

My present invention relates to air cleaners for internal combustion engines and, as a major feature, involves extremely simple and highly efficient means for detachably coupling the air cleaner to the intake port or passage of the carburetor. Generally stated, the invention consists of the novel devices, combinations of devices and arrangement of parts hereinafter described 10 and defined in the claims.

In the accompanying drawings, which illustrate the invention, like characters indicate like parts throughout the several views.

Referring to the drawings:

15 Fig. 1 is a view chiefly in side elevation but with some parts removed and some parts in section, showing the improved air cleaner applied to the intake port of the carburetor of an internal combustion engine;

20 Fig. 2 is a front elevation of the parts shown in Fig. 1;

Fig. 3 is a section taken on the line 3—3 of Fig. 2; and

25 Fig. 4 is an inner end elevation of the air cleaner removed from working position, some parts being broken away.

The particular carburetor illustrated is of a type commercially used in connection with a small two-cycle internal combustion engine applied for operating washing machines, but it is evident that the carburetor might be used in various other applications. It is important, however, that the carburetor be of a type provided with an exposed annular enlargement or seat of a nature presently to be described.

Referring briefly to the parts of the carburetor illustrated, the numeral 5 indicates the body thereof, which is bolted or otherwise secured to the engine crank case 6 and communicates with the intake passage thereof. The numeral 7 indicates the stem of the throttle valve and the numeral 8 the depending gasoline intake tube, which latter 40 draws gasoline from a reservoir, not shown

in the drawings, but which, in practice, is suitably secured to the carburetor body 5. In this particular carburetor, the air intake port 9 is at the upper portion thereof and this port 9, at its outer portion, is formed 50 with an annular enlargement 10 that affords a coupler seat. This seat 10 is somewhat smaller in diameter at its outermost portion than it is at its innermost portion and is preferably turned in the form of a truncated 55 cone having outward taper. It has already been indicated that the carburetor may take various different forms, but it is important that the intake port thereof be provided with the seat 10 or the equivalent thereof. 60

An air cleaner for the above purpose and particularly one for use in connection with the small carburetor such as used with small internal combustion engines, should not only be small but of extremely simple construction 65 and yet of high efficiency, and it should be capable of very quick and easy application to the carburetor and removal therefrom. In accordance with these requirements, the body of the carburetor is preferably formed with 70 a cylindrical portion 11 and a truncated conical portion 12, the contracted portion of which terminates in a neck 13 having an external channel. The outer flange of the channeled neck 13 is of such diameter that it 75 will pass very freely through the contracted outer portion of the seat 10. Seated in the channeled neck 13 is a spring metal coupling ring 14 preferably formed from round spring steel wire that is split at one portion at 14^a. 80 This coupling ring 14 is of such normal diameter that it fits with clearance around the bottom of the channel of the neck 13 and has an external diameter somewhat greater than the internal diameter of the seat 10 and, 85 normally, said ring 14 projects diametrically out of said channel or diametrically beyond the outside flange of the channel so that it is always exposed for frictional contact with the seat 10 and is adapted to be contracted 90

when inserted into said seat. With this arrangement, to couple the air cleaner to the carburetor, it is only necessary to force the same axially so as to press the spring ring 14 into the seat 10 under compression, and 5 when this is done, the said ring will so securely hold the air cleaner in working position that it will not accidentally be moved from working position. Nevertheless, it is 10 a comparatively easy matter, by the application of hand power to the air cleaner and by giving the same a slight rocking movement rather than a direct axial outward pull, to detach the air cleaner from the carburetor.

15 The air cleaner is completed by the application of two concavo-convex perforated disc-like heads 15 and 16, the former of which is clinched around the flanged outer edge of 20 the cylindrical body portion 11 and the latter of which is seated against the shoulder formed by the junction of the portions 11 and 12. A filler 17, of loose fibrous material, fills the space between the heads 15 and 16. 25 The two heads 15 and 16 are preferably set with their convex faces in the same direction, so that the two discs are substantially parallel.

What I claim is:

30 1. An air cleaner having a contracted neck portion formed with an external channel and in said channel an expandible and contractible split spring coupling ring adapted for engagement with a seat into said channel neck is insertable.

35 2. An air cleaner having a cylindrical body portion containing a filtering material and provided at its delivery end with a truncated conical contracted portion terminating in a neck affording an air delivery 40 port and having an external channel, and an expandible and contractible split coupling ring seated in said channel with clearance from the bottom thereof so that it may be contracted, the outer portion of said ring 45 normally projecting out of said channel so that it will engage a seat into which said channeled neck is inserted.

50 3. For use with a carburetor having an intake port formed with an annular coupling seat of less diameter at its outermost than at its innermost portion, an air cleaner having a neck affording an air delivery passage and formed with an external channel, said 55 neck being adapted for free insertion into said coupling seat, and a split spring coupling ring seated in the channel of said neck, said ring normally having clearance from the bottom of said channel and having a normal external diameter greater than that of 60 the outside flange of said channel and greater than the diameter of the outer edge portion of said coupling seat.

35 4. The structure defined in claim 1 in which said contracted neck portion is made

short by termination thereof substantially at the outer wall of said channel so that said ring may be engaged with and disengaged from its seat by a slight rocking movement.

5. The structure defined in claim 2 in 70 which said contracted neck portion is made short by termination thereof substantially at the outer wall of said channel so that said ring may be engaged with and disengaged from its seat by a slight rocking movement. 75

In testimony whereof I affix my signature.
FRANK A. DONALDSON.

CERTIFICATE OF CORRECTION.

Patent No. 1,787,235.

Granted December 30, 1930, to

FRANK A. DONALDSON.

It is hereby certified that error appears in the printed specification of the above numbered patent requiring correction as follows: Page 2, line 34, claim 1, after the word "into" insert the word which; and that the said Letters Patent should be read with this correction therein that the same may conform to the record of the case in the Patent Office.

Signed and sealed this 27th day of January, A. D. 1931.

(Seal)

**M. J. Moore,
Acting Commissioner of Patents.**
